DIAL FOR WATCHES OR CLOCKS

Filed March 1, 1926

Inventor

Julie Jactot Guillarmod
By her Attorney
Dean Fairbank Olmsted & Hirsch

UNITED STATES PATENT OFFICE.

JULES JACOT GUILLARMOD, OF NEW YORK, N. Y.

DESIGN FOR A DIAL FOR WATCHES OR CLOCKS.

Application filed March 1, 1926. Serial No. 16,706. Term of patent 14 years.

To all whom it may concern:

Be it known that I, JULES JACOT GUILLARMOD, a citizen of the Swiss Confederacy, and residing at New York, in the county of New York and State of New York, have invented a new, original, and ornamental Design for Dials for Watches or Clocks, of which the following is a specification, refer-

ence being had to the accompanying drawings, forming part hereof.

The figure is a face view of the dial.

I claim:

The ornamental design for a dial for watches or clocks.

JULES JACOT GUILLARMOD.
